Design No. 481.

James L. Jackson.
Design for a Gazebo Frame and Seats.

Patented 10th August 1850. -

Dec. 481

James L. Jackson of New York, N.Y.
Letters Patent Dated Aug 10th 1852 (No 481)

The schedule referred to in these Letters Patent and making part of the same

To all whom it may concern:

Be it known that I, James L. Jackson, of the City, County, and State of New York, have invented or produced, a new and original design for a Grate frame and Fender, and I do hereby declare the following to be a full, clear, and exact description of the same reference being had more particularly to the accompanying drawing, representing one half of the ornamental design in full, and the other half in outline only.

The outer margin of the grate frame, which is rectangular is embellished with a plain delicate moulding a, and the inner margin which is perpendicular for about two thirds of its height is bordered with a light cable moulding b. From the top of the straight part of the jamb-pieces of the frame, sweeps around a semi-circular arch, the moulding b, also extending around with it, until it meets a similar ornament on the opposite jamb-piece. From the moulding b, extending outwards there is a broad cavetto moulding c, flanked by a large & highly

raised cable moulding *d*, with a few plain broad mouldings outside of it. In the extreme upper corners of the frame, are entwined scrollwork figures *e*, terminating in pointed leaves *f*. The shaded line *x*, represents the outline of a cross section through the frame showing the elevation of the different ornaments.

The fender extends entirely across the bottom of the frame and has over its centre a highly wrought figure *g*, terminating in lozenges *h*, and underneath the top part, on a plain ground, is a series of alternate open work *i*, and rosettes *k*, extending entirely across the fender. Underneath this, and parallel with it, is a series of alternate open work *l*, and scroll work *m*, which latter is embraced at top between reversed volutes *n*, and terminating at bottom in pendants *o*.

The ends of the fender are finished with pilasters *p*, upon which it stands—the whole making a highly wrought ornamental casting in alto relieve and open work, of the Elizabethian style.

Having thus fully described and represented the nature of my design, what I claim therein as new and desire to secure by Letters Patent is the combination and arrangement of the ornamental figures herein represented and forming an ornamental design for a grate frame and fender.
